REFRIGERATOR CAR

Kurt E. Zeidler, Pittsburgh, Pa., assignor to
Standard Railway Equipment Manufacturing
Company, Chicago, Ill., a corporation of Dela-
ware

Application August 1, 1938, Serial No. 222,382

9 Claims. (Cl. 62—16)

This invention relates to refrigerator cars used to transport perishable commodities at a temperature within a predetermined range. This necessitates use of a cooling means in summer and a heating means in winter.

A refrigerator car comprises insulated walls, roof and floor and, when used in warm weather, a means for cooling the air as it circulates about the car. The cooling means may be fresh water ice, a mixture of ice and salt, a brine solution or a eutectic ice consisting of frozen brine. Said means may be placed at the ends of the car and separated by bulkheads from the lading compartment or may be suspended immediately below the ceiling.

The invention applies particularly to cars in which there are preferably a plurality of refrigerant containers near the roof, there being hatches in the roof above the containers for the deposit of refrigerant therein. The containers have foraminous walls through which air may circulate and be cooled by the refrigerant. A drip pan or partition is provided below the container to catch and drain the melted ice dripping from the container. A flue is preferably provided to communicate between the passage above the drip pan and the space between the floor rack and the floor.

Co-pending Gilpin application, Serial No. 222,363, filed August 1, 1938, discloses the bottom, or part of the bottom, of the container hinged and also the drip pan, or a part thereof, hinged. My invention consists of improvements in the construction shown by Gilpin. These improvements and the advantages resulting therefrom are as follows:

The removable part of the container bottom is mounted upon and secured to the drip pan or partition. This construction requires the use of only one hinge and latching mechanism, instead of two, as shown by Gilpin. The resultant advantages are less labor required for operation, fewer working parts to fail during service, and fewer working parts to wear out, therefore, it is an object of this invention to mount the bottom of the refrigerant container, or a part thereof, upon a hinged drip pan.

Another object of the invention is to associate a spring with the drip pan and car structure in such a way that the spring tends to return the drip pan and container bottom to their horizontal positions and so that a downwardly swinging movement of the drip pan and container bottom is yieldingly resisted by the spring. When a man attempts to lower the drip pan with container

bottom secured thereto, he is liable to be injured by the sudden dropping thereof. This is particularly dangerous when a large amount of ice is supported by the bottom. The spring will partly resist the tendency of the drip pan to drop suddenly and thus decrease the danger to the operator. After the ice has been removed from the container, the bottom must be replaced. This operation requires that the operator be in an awkward position in which he may be unable to exert enough force to replace the container bottom. The spring exerts a force which partly or wholly tends to return the drip pan and container bottom to the closed position.

In the drawings:

Fig. 1 is a vertical transverse section of a refrigerator car equipped with my invention. It is on line 1—1 of Fig. 5 and shows the container bottom closed on the left and open on the right.

Fig. 2 is a partial transverse section on line 2—2 of Fig. 5 showing the rigid portion of the container bottom.

Fig. 3 is an enlarged fragmentary section on line 3—3 of Fig. 4 showing details of the spring assembly.

Fig. 4 is a horizontal section on line 4—4 of Fig. 1 having a part of the container bottom broken away.

Fig. 5 is a vertical longitudinal section on lines 5—5 of Figs. 1 and 2.

Fig. 6 is a fragmentary section on lines 6—6 of Figs. 1 and 4.

Figs. 7 and 8 show modified constructions.

In Figs. 1 and 2 the usual parts of a refrigerator car are shown, such as center sill 2; side sills 3; underframe cross members 4; sub-floor 5; floor 6; floor rack 7; side sheathing 8; side lining 9; auxiliary walls 10 providing the flues 11; side plates 12; outer roof sheets 13; running boards 14; ceiling 15; hatch frames 16 surrounding the hatches 17; refrigerant containers 18; drip pans or partitions 19; upright walls 20 forming the duct 21 and insulation 22.

The foraminous refrigerant container 18 preferably comprises beams 31 extending between and secured to the side wall structure 30; foraminous sides 32 and a foraminous bottom 33 extend between and are supported by the beams 31. The beams 31 preferably consist of perforated webs 34 and upper and lower chords 35—36. The sides 32 may be wire mesh, expanded metal, perforated sheet, or other foraminous material.

The bottom 33 of the container 18 preferably comprises a plurality of inverted channel shaped parallel slats 40. The slats 41 near the center of

the container (i. e., under the hatch 17) are rigidly secured to and supported by the beams 42-43, said beams also serving as the lower chords of the sides 32. The non-rigid sections of the bottom 33 are at the ends of the container 18 and comprise inverted channel shaped slats 44 shorter than the clear distance between the beams 42 and 43. As shown in Fig. 6, the slats 44 are supported above and secured to the drip pan 19 by the element 45 having portions 46 adjacent the slats 44 alternating with portions 47 adjacent the drip pan 19.

The drip pan is secured to a plurality of arms 55 which are pivoted at fulcrums 56. The fulcrum 56 is shown in Figs. 1-3 secured to the beams 42 of the container 18. Although this construction is to be preferred, it is understood that any arrangement in which the fulcrum is supported by the car structure is included within the scope of this invention. For example, Fig. 7 shows the fulcrum 56 mounted on a bracket 57 supported by the wall structure 30 of the car.

A plurality of springs 65 are arranged so that the force exerted by said springs tends to rotate the arms 55 in a counter-clockwise direction about the fulcrums 56. The upper end of each spring 65 bears against the horizontal portion 66 of the bracket 67, the vertical portion 68 of said bracket 67 being secured to the side wall structure 30. A rod 69 having a spring seat 10 attached to the lower end thereof is pivotally connected to the arm 55 by the pin 11; thus, during any downward movement of the drip pan 19, the spring 65 is compressed between the horizontal portion 66 and the seat 10. The force thus exerted by the spring 65 tends to return the partition 19 to its normal horizontal position.

A plurality of supports 15 extend between the containers 18 and have straps 16 swingably suspended therefrom. The upright walls 20 are secured to the straps and serve the double purpose of forming a duct 21 for upward movement of air and of supporting the drip pan 19. A latch-like mechanism 11 fastened to the wall 20 holds the drip pan 19 in a horizontal position but release of the latch 11 allows the drip pan and container bottom to swing downwardly against the force exerted by the spring.

Fig. 8 shows a modified construction designed for the partial retention of brine. The bottom 85 of the container 18 is imperforate and has an upwardly projecting flange 86 entirely surrounding the bottom 85 to serve as a stiffener and to retain brine to the top of the flange 86. The upper part of the container 18 comprises foraminous walls 87. The bottom 85 is supported upon the drip pan 19 by the elements 45 and associated with the arm 55 and spring 65 as previously described. The drawings show the arm 55 hinged to the bracket 88 which is supported from the side wall structure of the car. The arm 55 may also be hinged to the container 18 or any other part of the car structure and be within the scope of the invention. The flange 86 retains a considerable amount of brine to insure a low temperature and the foraminous upper walls 87 allow the air to contact the ice and also facilitate ventilating the car.

When it is desired to remove the ice from the container 18 the latch 11 is released and the drip pan 19, to which the container bottom 33 is secured, is allowed to swing downwardly. The weight of drip pan 19, container bottom 33, and ice resting on said bottom is partly resisted by the force of the spring 65, thus making the work 75 of the operator easier and safer. Then, when

the ice has been removed the spring 65 partly or wholly returns the drip pan 19 and container bottom 33 to their closed positions.

The drawings show the entire drip pan 19 hinged and the end portions 44 of the container bottom 33 separate from the container and secured to the drip pan. It is understood that other arrangements, such as supporting the entire container bottom upon the drip pan or hinging only the part of the drip pan supporting the container bottom, are only minor variations and are included within the scope of the invention.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

20

I claim:

1. In a refrigerator car having spaced apart walls, a main floor and a roof provided with a hatch in combination with a refrigerant container below the hatch, a substantially horizontal drip pan below said container, the bottom of said container being secured to the drip pan independently of the rest of the container, said drip pan and the bottom of said container being hinged to the car structure for simultaneous swingable movement to remove the refrigerant from the container, and means to detachably secure said drip pan in its horizontal position.

2. In a refrigerator car having spaced apart walls, a main floor and a roof provided with a hatch in combination with a refrigerant container below the hatch, a substantially horizontal drip pan below said container, a part of the bottom of said container being secured to the drip pan independently of the rest of the container, said drip pan and said part of the bottom of said container being hinged to the car structure for simultaneous swingable movement to remove the refrigerant from the container, and means to detachably secure said drip pan in its horizontal position.

3. In a refrigerator car having spaced apart walls, a main floor and a roof provided with a hatch in combination with a refrigerant container below the hatch, the bottom of said container being hinged to the car structure for swingable movement to remove the refrigerant from the container, and means tending to return the bottom of said container to a substantially horizontal position.

4. In a refrigerator car having spaced apart walls, a main floor and a roof provided with a hatch in combination with a refrigerant container below the hatch and adjacent one of said walls, a foraminous floor positioned above the main floor to provide a space therebetween, a substantially horizontal partition, below said container and spaced therefrom to provide a passage therebetween, a vertical flue associated with one of said walls and communicating between said passage and said space, the bottom of said container being secured to the partition independently of the rest of the container, said partition and the bottom of said container being hinged to the car structure for simultaneous swingable movement to remove the refrigerant from the container, and means to detachably secure said partition in its horizontal position.

5. In a refrigerator car having spaced apart walls, a main floor and a roof provided with a hatch in combination with a refrigerant con-

70

- tainer below the hatch, the bottom of said container being hinged to the container for swingable movement to remove the refrigerant from the container, means to detachably secure said bottom in its horizontal position, and a spring positioned so that a downwardly swinging movement of the bottom of said container is yieldingly resisted by the spring.
5. A structure as defined in claim 1 including means tending to return said drip pan and the bottom of said container to a substantially horizontal position.
10. A structure as defined in claim 1 including
6. A structure as defined in claim 1 including means tending to return said drip pan and the bottom of said container to a substantially horizontal position.
7. A structure as defined in claim 1 including
- a spring positioned so that a downwardly swinging movement of the drip pan is yieldingly resisted by the spring.
8. A structure as defined in claim 2 including means tending to return said drip pan to a substantially horizontal position.
9. A structure as defined in claim 1 wherein the means for securing the bottom of said container to the drip pan comprises an element having portions adjacent said bottom alternating with portions adjacent said drip pan.
10. A structure as defined in claim 1 wherein the means for securing the bottom of said container to the drip pan comprises an element having portions adjacent said bottom alternating with portions adjacent said drip pan.
